COMBINED SAFETY CAP AND TEMPORARY STOPPER FOR A CONTAINER

Glenn H. Morris, 4203 Highwood Drive,
Chattanooga, Tenn. 37415

Filed May 24, 1973, Ser. No. 363,638

Term of patent 14 years

Int. Cl. D9—07

U.S. Cl. D9—281

FIG. 3

FIG. 1

FIG. 2

FIG. 1 is a side elevational view of a combined safety cap and temporary stopper for a container showing my new design, the opposite side being substantially a mirror image thereof;

FIG. 2 is a top plan view thereof; and
FIG. 3 is a bottom plan view.

I claim:

The ornamental design for a combined safety cap and temporary stopper for a container, substantially as shown and described.
